MINING APPARATUS

Joseph F. Joy, Claremont, N. H., assignor to Sulivan Machinery Company, a corporation of Massachusetts

Application December 30, 1935, Serial No. 56,624

6 Claims. (Cl. 262—28)

This invention relates to mining apparatus, and more particularly to improvements in the control means for the adjusting and/or feeding means for the kerf cutter of a coal mining apparatus whereby an excessive load on the cutter adjusting and/or feeding means is automatically precluded.

It is very desirable, particularly in hydraulically fed and adjusted mining apparatus, to provide means for preventing deliberate overloading of the driving motor in an attempt to effect exceedingly rapid feed, and to prevent undue motor overload, or strains in the mechanism, in the event of inadvertent engagements of adjusted parts with obstructions.

An object of the present invention is to provide improved means for automatically precluding excessive cutter feed, thereby eliminating any possibility of motor overload due to excessive cutter feed. Another object is to provide improved means for automatically precluding overload of the cutter driving motor due to an excessive feeding pressure. A further object is to provide an improved control means for automatically reducing the feeding pressure when the load on the kerf cutter reaches a certain predetermined amount, thereby to prevent overloading of the cutter driving means. A still further object is to provide an improved automatic control means for the hydraulic fluid system so that when the kerf cutter becomes overloaded due to a too great hydraulic feeding pressure in the fluid system, the feeding pressure is automatically reduced. Still a further object is to provide improved means for preventing motor overload and/or excessive strains in the apparatus due to inadvertent failure to stop adjusting movements before obstruction by floor, ribs, roof, etc. Yet another object is to provide an improved automatic control valve for the hydraulic fluid system, the valve being operated electrically by a solenoid connected in the motor circuit so that when the driving motor becomes overloaded the solenoid becomes energized to effect opening of the valve, thereby to reduce the hydraulic pressure. Still another object is to provide an improved means for automatically controlling the feeding and/or adjusting pressure on the kerf cutter, thereby removing from the operator the control of the feed beyond a certain predetermined feeding pressure, to prevent automatically overloading of the driving motor due to excessive feed and to prevent harm should there be carelessness in adjusting the apparatus. A still further object of this invention is to provide an improved automatic con-

trol means for regulating the feeding pressure substantially in accordance with the requirements of the cutting encountered by the kerf cutter, within certain predetermined limits. Further objects and advantages of the invention will, however, hereinafter more fully appear.

In the accompanying drawings there are shown for purposes of illustration two forms which the invention may assume in practice.

In these drawings,—

Fig. 1 is a plan view of a coal mining apparatus having embodied therein one illustrative form of the improved automatic control means, with the kerf cutter in horizontal cutting position.

Fig. 2 is a side elevational view of the mining apparatus shown in Fig. 1, with the kerf cutter in vertical cutting or shearing position.

Fig. 3 is an enlarged view in longitudinal section taken substantially on line 3—3 of Fig. 1, showing the kerf cutter driving means.

Fig. 4 is a vertical sectional view through one illustrative form of the automatic control valve.

Fig. 5 is a view similar to Fig. 4, showing a modified form of automatic control valve.

Fig. 6 is a diagrammatic view showing the hydraulic fluid system.

Fig. 7 is a wiring diagram of the motor circuit.

In this illustrative construction both forms of the improved control means are shown embodied in a coal mining apparatus of the same general character as that disclosed in my copending application Ser. No. 20,826, filed May 10, 1935, although it will be evident that the improved control means may be associated with mining apparatus of various other types. The mining apparatus disclosed herein comprises a portable base 1 in the form of a truck frame 2 mounted on wheels 3 adapted to run along a mine trackway 4. The truck frame 2 has mounted thereon, at its forward end, a horizontal turntable 5 rotatable about a vertical axis and in turn having pivotally mounted thereon at 6 for vertical swinging movement with respect thereto an elongated arm structure or boom 7. The arm structure or boom has mounted thereon at its forward extremity for rotation about an axis extending longitudinally of the arm structure a revolving head 8 in turn having pivotally mounted thereon to swing relative thereto about an axis 9 at right angles to the head axis a cutter support 10 carrying a kerf cutter 11. The kerf cutter is in the form of an elongated plate cutter bar 12 having mounted for circulation orbitally about its margin an endless cutter chain 13. Supported at the rearward portion of the swingable arm structure 55

or boom 7 is an electric driving motor 14 having its power shaft 15, as shown in Fig. 3, extending longitudinally of the arm structure and connected through a coupling 16 to a longitudinal shaft 17 suitably journaled within the arm structure, with its axis in coincidence with the revolving head axis. Keyed to the forward end of the shaft 17 is a bevel gear 18 which drives, through bevel gearing in a manner clearly described in the above mentioned copending application, a bevel gear 19 connected to a shaft 20. The shaft 20 has fixed thereto a chain sprocket 21 which engages and drives the endless cutter chain 13. Supported within the truck frame is a pump 25 driven by a motor 26, and this pump is adapted to supply hydraulic pressure to hydraulic cylinders 27, 27 for rotating the turntable 5, hydraulic cylinders 28 for vertically swinging the arm structure 7, hydraulic cylinders 29, 29 for revolving the head 8, and a hydraulic cylinder 30 for swinging the cutter support 10. Also mounted within the truck frame is transmission means driven by the motor 26 for driving the truck wheels to propel the apparatus along the mine trackway both during transport and cutting operations in a manner clearly described in the above mentioned copending application. Referring to the hydraulic system shown in Fig. 6, it will be noted that the pump 25 is arranged in a tank 31 adapted to contain a liquid, preferably oil, and the pump, submerged in the liquid, is adapted to supply hydraulic pressure to the various hydraulically operated cylinder and piston devices of the apparatus. Arranged within the truck frame is a horizontal valve box 32 similar to that described in the above mentioned copending application, and this valve box has formed therein a series of horizontal valve bores, each containing a balanced-type sleeve valve for controlling the flow of hydraulic pressure to the various hydraulic cylinders. The discharge supply of the pump 25 is connected through a conduit 33 to the supply passage of the valve box 32, while the discharge passages of the valve box are connected through branched conduits 34, 34 to a conduit 35 leading to the tank 31. Conduits connect the hydraulic cylinders 27, 28, 29 and 30 with the valve box 32, and the valves in this valve box are operative to control the flow of hydraulic pressure through these conduits to the cylinders. As the various hydraulic cylinders and the hydraulic fluid system are clearly described in the copending application above referred to, further detailed description of the specific structure thereof is herein considered unnecessary other than to state that the cylinders 29 may be operated to revolve the head 8 to move the kerf cutter into horizontal and vertical cutting positions, that the cylinders 27 may be operated to rotate the turntable to swing the arm structure about the turntable axis to swing the kerf cutter horizontally during the cutting operation, and that the hydraulic cylinders 28 may be operated to swing the arm structure 7 about its pivot with respect to the turntable to swing the kerf cutter vertically during the cutting operation.

As previously stated, without the provision of the improved automatic control valve it is possible for the machine operator to regulate the control valves in the valve box 32 so that the pressure in the cylinders 27 and 28 may reach an excessive amount so that the feeding pressure on the kerf cutter during either of its horizontal and vertical cutting operations becomes too great, and as a result, the cutter driving motor 14 be-

comes overloaded, causing injury thereto, such as overheating of its armature and burning out of the motor windings. To overcome such overloading of the cutter driving motor, the automatic control valve, generally designated 40, is inserted in the hydraulic system so that when the feeding pressure on the kerf cutter reaches a predetermined amount, the valve operates automatically to reduce the pressure in the hydraulic system, thereby to preclude overloading of the cutter driving means. This improved automatic control valve, as shown in Fig. 4, comprises a valve casing 41 having a chamber 42 connected through a pipe 43 to the supply conduit 33 of the hydraulic system. Also formed in the valve casing is a chamber 44 connected through a passage 45 with the chamber 42, and this chamber 44 is connected through a pipe 46 with the discharge conduit 35 of the hydraulic system. Surrounding the passage 45 is a valve seat 47 on which a valve 48 is adapted to seat for cutting off communication of the chamber 42 with the chamber 44. This valve has a valve stem 49 passing through a stuffing box 50 mounted within the valve casing, and the upper extremity of this valve stem 25 is connected to the armature 51 of a solenoid 52. This solenoid is supported by a frame 53 secured by bolts 54 to arms 55 formed integral with the valve casing 41, and interposed between the top plate 56 of the solenoid frame and the upper end 30 of the cylinder armature 51 is a coil spring 57 constantly urging the valve 48 toward its seated position. As shown diagrammatically in Fig. 7, the series field of the cutter driving motor 14 is indicated by the numeral 58, the shunt field by 35 the numeral 59 and the contactor controller generally at 60. The coil 61 of the solenoid 52 is connected by a line 62 in the series field of the motor. When the motor 14 becomes overloaded for any reason, and the electrical energy in the series field 58 and the line 62 becomes sufficiently high, the coil 61 is energized so strongly that the armature of the solenoid is drawn upwardly from the position shown in Fig. 4 to open the valve 48. As a result, fluid in the supply conduit 33 is bypassed through the pipes 43 and 46 to the discharge conduit 35, reducing the pressure of the fluid in the supply conduit. In the event of carelessness in adjusting the apparatus during movement of the kerf cutter in the desired relation with respect to the work, for instance if the arm structure should strike the mine wall or the roof or floor during adjustment of the kerf cutter, means is provided for preventing automatically overloading of the pump driving motor. This improved control means is similar to that for the cutter driving motor and comprises an automatic control valve 63, similar to that shown in Fig. 4, having its solenoid 64 connected by a line 65 in the series field 66 of the motor 26. The numeral 67 designates the contactor controller for the motor 26. As in the control for the motor 14, when the load on the motor 26 becomes too great, the electrical energy in the series field 66 and the line 65 becomes sufficiently high so that the coil of the solenoid is energized, drawing its solenoid core upwardly to open the valve, and as a result the liquid in conduit 33 is by-passed through conduits 43 and 69, through the conduit 46 and back to the tank 31.

In the modified construction shown in Fig. 5, the pressure of the fluid in the hydraulic system is controlled automatically in accordance with the requirements of the cutting encountered by the kerf cutter during the cutting operation. In 75

this construction there is shown a valve casing 70 having formed therein a valve chamber 71 in which is reciprocably mounted a slide valve 72 having an upward projection, herein forming the armature of a solenoid 73, mounted on the upper portion of the valve casing. A coil spring 74 acting on the upper end of the slide valve constantly urges the latter toward its lowermost position. This slide valve is of the balanced type having spaced piston heads 75, 76 connected by the reduced body portion 77 providing an annular groove 78 surrounding the valve body between the piston heads. Communicating with this groove is a passage 79 connected by a pipe 80 to the supply conduit 33 of the hydraulic system. Formed in the wall of the valve chamber is a groove 81 connected by a passage 82 through a pipe 85 to the discharge conduit 35 of the hydraulic system. V-shaped notches 83 are formed in the wall of the valve chamber and communicate with the annular groove so that a graduated flow of fluid from the supply passage to the annular groove is obtained. The coil 84 of the solenoid is connected by the wire 62 in the series field of the cutter driving motor so that when the load on the motor varies, the amount of current supplied by the wire 62 to the solenoid coil is correspondingly varied, and as a result, the slide valve is moved within its bore to vary the flow of fluid from the supply passage to the discharge passage automatically in accordance with the motor load.

The mode of operation of both forms of improved control means for the kerf cutter feeding means will be clearly apparent from the description given. During either the horizontal cutting operation, as shown in Fig. 1, or the vertical cutting operation, as shown in Fig. 2, the hydraulic system is operated under the control of the manual control valves in the valve box 32 to supply liquid under pressure to the hydraulic cylinders to effect swinging of the arm structure to move the kerf cutter arcuately in its plane. In the form of the invention shown in Fig. 4, in case the feeding pressure becomes too high during the arcuate swinging feeding movement of the kerf cutter during the cutting operation, the load on the driving motor 14 for the kerf cutter increases to a point within its maximum load range so that the electrical energy in the motor windings becomes sufficiently high, the coil 61 of the solenoid 52 is energized to draw the armature 51 of the cylinder upwardly, opening the valve 48 and by-passing the fluid in the supply conduit 33 through which hydraulic pressure is supplied to effect feed, through the pipes 43 and 46 to the return conduit 35, and as a result, the feeding pressure in the hydraulic system is substantially reduced. When the load on the cutter driving motor decreases to a point within its normal range of operation, the coil 61 of the cylinder 52 is substantially de-energized, thereby causing the coil spring 57 to move the armature 51 downwardly to close the by-pass valve 48 so that normal pressure within the hydraulic system is again attained. Overload of the motor 26, during adjustment of the kerf cutter, is automatically prevented by the automatic control valve 63, so that the pressure in the fluid system is automatically reduced in case the adjusting structure should strike an abutment, such as the mine wall, or roof or floor. It is accordingly evident that the improved electrically actuated valves in the hydraulic system are so arranged that when the current of the driving motors 14 and 26 reaches a predetermined amount, the hy-

draulic pressure is by-passed sufficiently to control the load on the driving motors within their maximum load range, thereby precluding the possibility of the machine operator overloading the driving motors, and any attempt on his part to supply excessive feeding and/or adjusting pressure to the kerf cutter is automatically prevented.

In the operation of the automatic control valve shown in Fig. 5, as the kerf cutter is fed arcuately in its plane during the cutting operation, the feeding pressure applied to the kerf cutter is automatically regulated in accordance with the requirements of the cutting encountered, and as the load on the cutter driving motor varies within certain limits the position of the slide valve is automatically varied, the valve moving up and down automatically to regulate the pressure in the hydraulic system, the slide valve controlling the amount of fluid by-passed past the valve automatically substantially in accordance with the load on the cutter driving motor, within certain predetermined limits. It will thus be seen that when the hardness of the coal encountered by the kerf cutter varies, the pressure in the hydraulic system is correspondingly varied, so that the feeding pressure is regulated automatically substantially in accordance with the requirements of the cutting encountered. Other uses and advantages of the improved automatic feed and/or adjustment control means will be clearly apparent to those skilled in the art.

While there are in this application specifically described two forms which the invention may assume in practice, it will be understood that these forms of the same are shown for purposes of illustration and that the invention may be further modified and embodied in various other forms without departing from its spirit or the scope of the appended claims.

What I claim as new and desire to secure by Letters Patent is:

1. In a kerf-cutting machine, in combination, a kerf cutter, hydraulically operated means for feeding the kerf cutter during the cutting operation, an electric motor for driving the kerf cutter, and means governed by the power taken by said motor for automatically reducing the pressure exerted by said hydraulically operated feeding means when the difficulty of cutting increases, said automatic pressure reducing means including a device movable to regulate the hydraulic pressure and a solenoid for controlling said device, said solenoid so connected relative to the motor circuit that a variation in motor current is attended by an alteration in the force exerted by said solenoid and said controlling device, when the current taken by said motor exceeds a predetermined amount, operating to preclude overloading of said cutter driving motor.

2. In a mining apparatus, in combination, a kerf cutter, an electric motor for driving said kerf cutter, hydraulically operated means for feeding the kerf cutter during the cutting operation, a by-pass valve for controlling the pressure in said hydraulically operated means, and a solenoid connected in the motor circuit for automatically opening said valve when the current taken by said motor exceeds a predetermined amount, thereby to preclude overload of said cutter driving motor.

3. In a mining apparatus, in combination, a kerf cutter, an electric motor for driving said kerf cutter, hydraulically operated means for

feeding the kerf cutter during the cutting operation including a hydraulically operated feeding motor, a pump, and a pump driving motor, and means for precluding overload of said kerf cutter driving motor while providing for rapid feed including a balanced valve for governing the pressure supply to said feeding motor, and controlling means for said valve including a solenoid traversed by the current supplied to said cutter driving motor for opening said valve on current increase.

4. In a mining apparatus, in combination, a kerf cutter, hydraulically operated mechanism for adjusting said kerf cutter into and supporting it in different planes, hydraulically operated means for effecting cutting feed of said kerf cutter when it is in any of said planes, a hydraulic system for supplying and controlling the fluid supplied to said hydraulically operated mechanism and means, means including an electric motor for actuating said kerf cutter to effect its cutting operation when fed in any of said planes, and means for precluding excessive overloading of said motor including valve means movable to reduce the pressure at which fluid is supplied to said hydraulically operated means, and controlling means for said valve means including a sole-

noid arranged to have the motor current pass therethrough.

5. In a mining apparatus, in combination, a kerf cutter swingable upwardly to cut a vertical kerf, hydraulic feeding means for effecting such swinging movement, an electric driving motor for said kerf cutter, and means for precluding feeding pressures overloading said motor but precluding reduction in feeding pressure to a value insufficient to support the kerf cutter, including a bypass and a controlling valve therefor governing the pressure at said hydraulic means, and a solenoid connected in series with said motor for controlling the position of said valve.

6. In a mining apparatus, in combination, a kerf cutter, an electric motor for driving said kerf cutter, hydraulically operated means for swinging the kerf cutter to effect a cutting operation, means for effecting operating-medium supply to said hydraulically operated means, and means for controlling the pressure supplied to said hydraulically operated means automatically to limit the load on said kerf-cutter driving motor, including a valve openable to reduce the feeding pressure and a solenoid for controlling said valve connected in series with said motor.

JOSEPH F. JOY.
